UNITED STATES PATENT OFFICE.

HERBERT S. MILLS, OF OAK PARK, ILLINOIS.

DESIGN FOR A CASING FOR WEIGHING-SCALES.

50,246.

Specification for Design.

Patented Jan. 30, 1917.

Application filed November 7, 1916. Serial No. 130,078. Term of patent 14 years.

To all whom it may concern:

Be it known that I, HERBERT S. MILLS, a citizen of the United States, residing at Oak Park, in the county of Cook and State of Illinois, have invented a new, original, and ornamental Design for Casings for Weighing-Scales, of which the following is a specification, reference being had to the accompanying drawing, forming a part hereof.

The figure is a perspective view of a casing for weighing-scales in accordance with my new design.

I claim:

The ornamental design for a casing for weighing-scales, as shown.

HERBERT S. MILLS.
